His Attorney.

UNITED STATES PATENT OFFICE.

OLIVER C. TRAVER, OF SCHENECTADY, NEW YORK, ASSIGNOR TO GENERAL ELECTRIC COMPANY, A CORPORATION OF NEW YORK.

SELECTIVE-CIRCUIT-CONTROLLING SYSTEM.

Application filed November 17, 1924. Serial No. 750,264.

This invention relates to the selective control of electric translating devices and it provides an improved arrangement of thermal responsive circuit controlling devices and

5 circuits for effecting the separate energization of the translating devices.

Although not limited thereto, the invention is particularly adapted to control the lamps of a dual intensity street lighting system 10 wherein the high intensity lamps are lighted during the earlier part of the night and lower intensity lamps are lighted during the remainder of the night.

In such systems it has been proposed here- 15 tofore to effect the changeover from the high intensity to the low intensity lamp by means of lamp switching relays located at each of the lighting units which are arranged to be operated upon a momentary de-energization 20 of the power supply lines for the lamps. The various forms of lamps switching relays with which I am familiar have required the use of electromagnets for controlling the switch mechanism, thus leaving something to be 25 desired in the way of a less expensive and more simple lamp switching device.

In carrying my invention into effect in the form which I now regard as a preferred form, circuit controlling switch mechanism is controlled by means of a pair of thermal responsive movable elements having different heat storage capacities, such as is fully described and claimed in my divisional application, 30 Serial No. 97,726, filed March 26, 1926, the 35 elements being arranged to be heated simultaneously responsive to the current in the circuit controlled by the switch mechanism and arranged so as to operate the switch mechanism responsive to the difference in 40 the rate of cooling of the elements upon a momentary interruption of the circuit.

For a better understanding of my invention reference is had to the following description when taken in connection with the accompanying drawings in which Fig. 1, diagrammatically illustrates a preferred form of thermal responsive switch mechanism embodying my invention together with a selective control system employing the same, and 45 Figs. 2 and 3 show the relative positions of the several operating parts of the thermal responsive switch mechanism during different 50 phases of operation thereof.

The novel features and combinations which I believe to be characteristic of my invention are pointed out with particularity in the appended claims.

Referring to Fig. 1, the thermal responsive switch mechanism comprises essentially the cooperating circuit controlling contacts 10, 11 and 12 and the thermal responsive movable elements 13, and 14. In the preferred form illustrated, the thermal responsive elements 13 and 14 are of the bi-metallic current conducting type and in accordance with my invention are designed to have substantially similar thermal characteristics of expansion while having different heat storage capacities. The thermal element 13 is suitably secured at one end to the stationary support 15 and carries the movable circuit controlling contact 10 at the free end thereof. It will be observed that the circuit controlling contacts 11 and 12 are mounted in fixed spaced relation upon opposite ends of yoke 16, the contact 11 being suitably insulated therefrom, and are supported in cooperating relation with the contact 10 by the thermal responsive element 14, one end of which is suitably secured to the stationary support 17 and the other end is secured to the yoke 16.

As will be more fully described in connection with the operation of my invention, the thermal responsive elements 13 and 14 are heated by a common energizing current and cooled by the surrounding air. Since the elements 13 and 14 have substantially similar thermal characteristics, each of the elements will flex substantially the same amount upon a given change of temperature thereof. However, due to the fact that the elements have different heat storage capacities, the rate of change of temperature thereof will vary when they are subjected to a common heating or cooling effect. Thus the element having the lesser heat storage capacity will respond to a given heating and cooling effect more rapidly than the element having the greater heat storage capacity and a resulting relative movement occurs between the contact members which is dependent upon the difference in the rate of change of temperature thereof. It will be evident that the relative heat storage capacities of the thermal responsive elements 13 and 14 may be varied by properly proportioning the relative mass

of the supports 15 and 17 with which the respective elements are in heat conducting contact as indicated in the drawing or by properly proportioning the mass of the elements themselves.

In the preferred form of thermal responsive switch mechanism illustrated, the thermal responsive elements 13 and 14 are given an initial bias such that when the elements 10 are at the same temperature, the contact 10 is maintained in firm engagement with the contact 12 and are each arranged to flex in the same direction when heated and cooled. The thermal responsive element 13 has a greater 15 heat storage capacity than element 14 and consequently the former responds more slowly to a heating or cooling effect than the latter.

As shown in Fig. 1, the thermal responsive 20 switch mechanism is connected to selectively control the energization of the electric translating devices 18 and 19 which may be assumed to be respectively the low intensity lamp and the high intensity lamp of a lighting 25 unit employed in a dual intensity street lighting system. In accordance with the usual practice, the lamps 18 and 19 are connected in series in a supply line or energizing circuit 20 and the switch 21 is located at the 30 power house or other convenient place in order to control the connection of the supply line 20 to a suitable source of power 22.

In order to separately control the energization 35 of the lamps 18 and 19, the thermal responsive switch mechanism is connected by suitable conductors as shown to establish a short circuit around the lamp 18 when the movable circuit controlling contact 10 is in engagement with the contact 12 and to similarly short circuit the lamp 19 when the contact 10 is in engagement with the contact 11.

As thus constructed and arranged the operation of my improved form of thermal responsive switch mechanism and control system employing the same is as follows.

Upon the operation of switch 21 from the open position to the closed position, the supply line 20 is energized from the source of supply 22 and since the low candle power 50 lamp 18 is short circuited, current flows from the supply line 20 through the thermal responsive element 14, the cooperating contacts 10 and 12, the thermal responsive element 13 and the high intensity lamp 19, thereby lighting the latter to furnish high intensity illumination. As the current flow continues, the thermal responsive elements 13 and 14 are heated and consequently flex in unison in the same direction and carry the cooperating circuit 55 controlling contacts 10, 11 and 12 as a unit into the position shown in Fig. 2. Due to the fact that the heat storage capacity of thermal responsive element 14 is less than that of element 13, the temperature of the 60 former will increase more rapidly and the ele-

ment 14 will tend to flex at a greater rate and thus force the contact 12 in firmer engagement with the movable cooperating contact 10. After the thermal responsive elements 13 and 14 finally reach a substantially 70 constant temperature, the contacts 10 and 12 are maintained in engagement due to the initial bias of the thermal elements and the high candle power lamp 19 continues to receive energizing current as shown in Fig. 2. 75

It will be evident that with my improved form of thermal responsive switch mechanism, a temporary failure of the supply source 22 or a temporary decrease in current in the supply line 20 due to accidental ground 80 or other causes occurring during the operation of the lighting system will not produce a separation of the contacts 10 and 12 unless continued for an appreciable length of time. This is due to the fact that the support 17 as 85 well as the mass of thermal element 14 serve as heat storage masses to prevent too rapid cooling of the element 14.

If now it should be desired to deenergize the high candle power lamp 19 and energize 90 the low candle power lamp 18, the change-over is effected simply by opening the switch 21 for a short interval. This interrupts the heating current for both thermal responsive element 14 and 13 and each thereupon begins 95 to decrease in temperature at a rate dependent upon the heat storage capacity thereof. Since the heat storage capacity of thermal element 14 is relatively low, the temperature of this element will more rapidly decrease and the resulting flexure of the element will carry the circuit controlling contact 12 out of engagement with the contact 10 and operate the circuit controlling contact 11 into engagement therewith. During this limited time interval the movement of contact 10 by thermal element 13 is relatively small due to the fact that the larger heat storage capacity of thermal responsive element 13 causes the temperature of this element to decrease 100 at a much slower rate. After the engagement of contact 11 with contact 10, the element 13 actively opposes further movement of element 14, thus maintaining the contacts in 105 firm engagement.

The relative positions of the operating parts of the thermal responsive switch mechanism after this phase of operation are illustrated in Fig. 3. It will be evident that upon the reclosure of switch 21 current will flow 110 through the low intensity lamp 18, the thermal responsive element 13 and the cooperating contacts 10 and 11 and the high intensity lamp 19 will be short circuited. The heating effects of the current flowing through element 13 maintains this element flexed with the circuit controlling contact 10 in engagement with contact 11, as long as the low candle power lamp 18 is maintained energized. During 115 this time, no current flows through the 120

thermal element 14 and since the elements are now active in opposition a good electrical contact is secured.

When the low intensity lamp 18 is deenergized by the opening of switch 21, the thermal responsive element 10 is permitted to cool and after a sufficient time interval again will carry the circuit controlling contact 10 into engagement with the cooperating contact 12 as shown in Fig. 1. Thus the electro responsive switch mechanism is returned to its initial position in which the low intensity lamp 18 is short circuited and the thermal responsive elements 13 and 14 are connected in series with the high intensity lamp 19 to be energized simultaneously therewith upon the reclosure of switch 21.

From the foregoing it will be obvious that in a lighting system employing a plurality of thermal responsive switches embodying my invention, even though the several switch mechanisms may become unsynchronized due to grounds, accidental interruptions of the supply circuit, or other cause occurring during the operation of the lighting system, nevertheless each of the switch mechanisms will automatically return to corresponding initial position upon the interruption of the supply circuit for a sufficient time interval.

In accordance with the provisions of the patent statutes I have described the principle of operation of my invention together with the apparatus which I now consider to represent the best embodiment thereof, but I would have it understood that the apparatus shown is only illustrative and that the invention may be carried out by other means.

What I claim as new and desire to secure by Letters Patent of the United States is:—

1. In combination, a plurality of electric circuits, controlling means therefor including thermal responsive elements having different heat storage capacities and arranged to be heated in accordance with the current flow in at least one of the circuits and translating devices connected in said circuits to be selectively controlled responsively to the difference in rate of change of temperature of said elements upon variation in the heating current thereof.

2. In combination, controlling means for electric circuits including relatively movable thermal responsive elements connected to be electrically heated by the current in at least one of the electric circuits and having dissimilar movements upon the cooling thereof, a pair of translating devices connected in said circuits, and switch mechanism jointly controlled by said thermostatic elements for short circuiting one of said translating devices prior to said dissimilar movements thereof and for short circuiting the other translating device after said dissimilar movements thereof.

3. The combination with a pair of electric circuits, a plurality of relatively movable

translating devices, of switch mechanism for separately energizing said devices, means for operating said switch mechanism responsively to a momentary interruption of the energizing circuit of said devices comprising a pair of thermal current responsive elements having substantially similar thermal characteristics of expansion and different heat storage capacities.

4. The combination with a pair of electric translating devices, of switch mechanism operable between two circuit controlling positions for separately energizing said devices, said switch mechanism being biased to one of said positions, a pair of thermal responsive elements having different heat storage capacities and arranged to operate said switch mechanism to the other position responsively to the difference in the rate of change of temperature of said element, and connections controlled by said switch mechanism for energizing both of said elements when said switch mechanism is in the biased position and for separately energizing the thermal element of greater heat storage capacity when the switch mechanism is in the other position.

5. The combination with a pair of electric translating devices connected in series circuit, of switch mechanism operable between two circuit controlling positions for separately establishing a shunt circuit around each of said devices, said switch mechanism being biased to one of said positions, a pair of bimetallic thermal current responsive movable elements connected to be heated responsively to the current in the shunt circuit normally established by said switch mechanism and arranged to operate said switch mechanism to the other circuit controlling position upon a momentary interruption of said series circuit, and connections whereby the thermal element of greater heat storage capacity is heated responsively to the current in the other shunt circuit upon the reclosure of said series circuit to maintain said switch mechanism in the other position against its bias.

6. In combination, a plurality of electric circuits and a plurality of thermal responsive elements having different thermal characteristics and means controlled by said elements to effect a selective control of said circuits depending on the difference in the rate of change of the temperature of the elements.

7. In combination, a plurality of electric circuits and a plurality of relatively movable thermal responsive elements having different thermal characteristics and arranged to be heated in accordance with the current flow in at least one of the circuits, and switch mechanism jointly controlled by said elements for effecting a selective control of said circuits depending on the difference in the rate of change of the temperature of the elements.

8. In combination, a plurality of electric

thermal responsive elements having different thermal characteristics, means for heating all the elements in accordance with the current flow in one of the circuits and for heating a portion of the elements in accordance with the current flow in another one of the circuits, and means controlled by the elements to effect a selective energization of the said circuits depending on the difference in the rate of 10 change of temperature of the elements.

9. In combination, a plurality of thermal

responsive elements having different thermal characteristics, a plurality of translating devices controlled thereby, and connections through which said elements effect a selective control of said devices depending on the difference in the rate of change of the temperature of the elements. 15

In witness whereof, I have hereunto set my hand this 15th day of November, 1924.

OLIVER C. TRAVER.
